MOLD FOR ICE CUBE OR THE LIKE

Elizabeth Camp Ebbott, New York, N. Y.

Application March 17, 1950, Serial No. 8,585

Term of patent 3½ years

(Cl. D67—3)

To all whom it may concern:

Be it known that I, Elizabeth Camp Ebbott, a citizen of the United States, and a resident of New York city, county of New York, and State of New York, have invented a new, original, and ornamental Design for a Mold for Ice Cube or the Like, of which the following is a specification, reference being had to the accompanying drawing, forming part thereof.

Fig. 1 is a perspective view of a mold for ice cube or the like, showing my new design;

Fig. 2 is a cross-sectional view taken substantially along the line 2—2 of Fig. 1; and

Fig. 3 is a plan view on a reduced scale.

I claim:

The ornamental design for a mold for ice cube or the like, substantially as shown.

ELIZABETH CAMP EBBOTT.
